US0D1004540S

(12) **United States Design Patent** (10) Patent No.: **US D1,004,540 S**
(45) Date of Patent: ** Nov. 14, 2023

(54) **POWER TOOL BATTERY**

(71) Applicant: **Shenzhen Waitley Power Co., LTD,**
Shenzhen (CN)

(72) Inventors: **Yuhang Wu**, Shenzhen (CN); **Zekun Li**, Shenzhen (CN); **Lianzhong Geng**, Shenzhen (CN)

(73) Assignee: **Shenzhen Waitley Power Co., LTD,**
Shenzhen (CN)

(**) Term: **15 Years**

(21) Appl. No.: **29/876,676**

(22) Filed: **May 25, 2023**

(51) LOC (14) Cl. **13-02**

(52) U.S. Cl.

USPC **D13/103**

(58) **Field of Classification Search**

Primary Examiner — Rosemary K Tarcza

(57) **CLAIM**

The ornamental design for a power tool battery, as shown and described.

DESCRIPTION

FIG. 1 is a front, right, top perspective view of a power tool battery showing our new design;

FIG. 2 is a back, left, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 7; and,

FIG. 10 is an enlarged view of the encircled area 10 of FIG. 7.

The broken lines shown in the figures depict portions of the power tool battery that do not form part of the claimed design.

1 Claim, 10 Drawing Sheets
